UNITED STATES PATENT OFFICE.

WILLARD O. WHITE, OF UNIONTOWN, PENNSYLVANIA.

DOOR FOR COKE-OVENS.

1,034,328.

Specification of Letters Patent. Patented July 30, 1912.

Application filed November 12, 1910. Serial No. 592,058.

To all whom it may concern:

Be it known that I, WILLARD O. WHITE, a citizen of the United States, residing at Uniontown, in the county of Fayette and State of Pennsylvania, have invented a new and useful Door for Coke-Ovens, of which the following is a specification.

This invention has reference to improvements in doors or closures for coke ovens, furnaces, and the like and while more particularly adapted to rectangular and beehive coke ovens it may be used with advantage in connection with other ovens or fire chambers.

15 The object of the present invention is to provide a device of this character wherein the metal parts are protected from overheating while provision is made for supporting fire brick or like material constituting the protecting material where the shapes of the fire bricks are such as to involve a minimum number of special brick molds while the bricks may be of moderate size to economize manufacture and repairs.

20 Furthermore, the present invention provides a door in which both the brick and metal parts are free to expand without danger of warping the metal framework and the brick and metal parts are so combined that the metal is capable of radiating heat on the cool side of the door while those metal parts which are subjected to most heat are easily renewable.

25 The invention also provides means whereby the brick space of the door may be considerably varied in height and width and without necessitating variation in the size of the metal parts so that the same metal parts are adaptable to either the front or discharge ends of ovens where the discharge end is wider than the front or pusher end.

30 The showing of the drawings is that of an oven door for the rectangular type of coke ovens, such oven being provided with a door at each end. For the beehive type of oven the arrangement of parts is practically the same but on a smaller scale. Other ovens or furnaces will require slight modifications in structure but not of the invention. Therefore the invention is not limited to the details of construction shown and described but may be varied so long as the salient features of the invention are retained.

35 The invention will be best understood from a consideration of the following detail description taken in connection with the ac-

companying drawings forming a part of this specification, in which drawings:

Figure 1 is a central vertical section through the door and oven. Figs. 2, 3 and 4 are edge and face views respectively of a fire brick used in connection with the door. Fig. 5 is a face view of an oven equipped with the present invention showing a modified form of supporting means for the door.

60 Referring to the drawings there are shown two adjacent coke ovens 1, 2, the door ends only being shown, and these ovens are assumed to be of the rectangular type where the ovens are similar one to the other and arranged side by side and in the particular instance shown, one oven is illustrated as somewhat more elevated than the other, it being a common practice to form the entire bank of ovens on a slight incline.

65 It is customary to build the doors in two sections, an upper section 3 and a lower section 4.

70 The upper section is a skeleton frame which comprises a plate 5 of appropriate size and shape with the lower edge having an inturned flange 6 terminating in an upturned rib 7 approximately parallel with the plate 5. The upper edge of the plate 5 is rounded in conformity with the arch of the 75 opening of the oven.

75 Attached to the upper end of the plate 5 is a bow plate or strip 8 provided at appropriate points with flat lugs or extensions 9 having at the free ends slots or grooves 10 adapted to receive bolts 11 by means of which the bow plate 8 is made fast to the door plate 5 with limited adjustment thereto. The bow plate 8 has along the edge remote from the lugs 9 a rib 12 which when 80 the plate 8 is made fast to the plate 5 is parallel with the said plate 5 but spaced therefrom by the width of the plate 8 and the thickness of the lugs 9.

85 The lower door member is provided with 100 a metal skeleton frame comprising a plate 13 formed at top and bottom with longitudinal flanges 14, 15 respectively projecting at right angles to the plane of the plate 13 and terminating at the edges remote from the plate 105 in ribs 16 extending approximately parallel with the plate 13, one toward the other.

90 The skeleton frames of the upper door and the plate 13 of the lower door are faced on the fire side with fire bricks 17, one of which 110 is shown in Figs. 2, 3 and 4 and this may be taken as typical of all the bricks making up

the fireside of the door, except that the arched edges of the bricks along the upper edge of the upper door are curved on substantially the arc of the arch of the oven. 5 Each brick 17 has one face 18 of such area that when all the bricks of the doors are in place the fire side of the door will be practically continuous with the edges of the bricks forming closely fitting joints, al- 10 though as will hereinafter appear, certain latitude in this respect is permissible. The other face 19 of each brick is of less area than the face 18 although of equal length, the face 19 being of less extent in the direc- 15 tion of the height of the brick than the face 18. Along the top and bottom portions of the face 19 where this portion of the brick joins the face 18 there is provided a longitudinal groove 20 while along those portions 20 of the brick which are set vertical when in place on the door, there are provided grooves 21 for a purpose which will presently appear.

When the bricks 17 are in place on the 25 door the vertical edges in which the grooves 21 are formed are in abutment throughout the thickness of the brick except where the grooves 21 occur, these grooves matching in the adjacent edges of the bricks. The top 30 and bottom edges of the sides 18 of the bricks 17 are also in engagement where the bricks are adjacent, but the like edges of the portions 19 of the bricks are separated by spaces determined by the height of these 35 portions 19 of the bricks, while the grooves 20 of one brick match the grooves 20 of adjacent bricks. The door is therefore formed of bricks in vertical series when the door is in place with the horizontal meeting edges 40 having longitudinal channels formed by the meeting grooves 20. Seated in these channels are bars 22 of metal and these bars are connected with the respective frames 5 and 13 by bolts 23 surrounded between the re- 45 spective plates 5 and 13 and the bars 22 by spacing sleeves 24.

The rib 7 of the lower flange 6 of the door plate 5 engages the groove 20 on the lower 50 edge of the lower series of bricks 17 of the door 3, while the upper series of bricks 17 is engaged by the bowed strip or plate 8 with its rib 12 seated in the grooves 20 of these bricks, the other bricks intermediate of the top and bottom rows being held 55 by the bars 22 and bolts 23 with their spacing sleeves 24. The width of the plate 8 and of the flange 6 and also of the spacing sleeves 24 determine the distance from the outer face of the bricks 17 and the inner 60 face of the plate 5, this plate being off-set an appropriate distance from the outer faces of the bricks 17. The rib 12 of the plate 8 and the rib 7 of the flange 6 together with the bars 22 firmly anchor the 65 bricks 17 to the plate 5 of the upper door

while the ribs 16 of the flanges 14 and 15 and the bar 22 firmly anchor the bricks of the lower door to the plate 13. The bars 22 may be as long as desired and the plate 8 is capable of adjustment vertically with 70 relation to the plate 5, considering the door as installed, and therefore doors varying considerably in size may be constructed without the necessity of providing other metal parts than those described, one size 75 or metal parts answering for doors of different sizes.

When in place the door 4 and the door 3 are superposed with the door 4 the lower door and resting on the floor of the oven. 80 When the bricks are assembled in the doors or door sections 3 and 4 the spaces provided by vertical grooves 21 in matching relation one to the other at the meeting edges of the bricks are filled with refractory packing so 85 that these joints are rendered tight.

The construction described furnishes ample provision whereby the bricks may be readily replaced without the necessity of entirely dismantling the door, and those 90 metal parts liable to damage may also be readily replaced. At the same time no metal parts are subjected to the direct action of the heat but are amply protected by the fire brick interposed between these metal parts 95 and the interior of the oven. Furthermore the metal supporting plates are spaced from the outer walls of the fire bricks so that transmitted heat has ample radiating space and the metal parts are correspondingly 100 protected from the effect of the great heat of the interior of the oven.

What is claimed is:—

1. A coke oven door consisting of a pair of frames disposed one above the other, 105 forming upper and lower door sections, gripping members formed integral with said frames, said frames, a stack of bricks in edged relation, said bricks being formed with grooves and disposed in an upper and lower set, 110 the grooves of the lower set receiving the gripping members formed integral with the lower frame, the lowermost bricks of the upper set receiving the gripping members formed integral with the upper frame, and a curved gripping member adjustably supported by the upper frame, said member engaging the uppermost bricks of the upper set.

2. A coke oven door consisting of a pair of frames disposed one above the other, gripping members formed integral with said frames, said frames forming the upper and lower sections of the door, a stack of bricks in edged relation, and disposed in upper 120 and lower sets, said bricks being formed with grooves, the grooves of the lowermost set of bricks receiving the gripping members formed integral with the lower frame, the lowermost bricks of the upper set receiving 125

the gripping members formed integral with the upper frame, and a curved gripping member adjustably supported by said upper frame, said member being formed with a flange arranged to engage the grooves of the uppermost bricks of the upper set.

In testimony that I claim the foregoing

as my own, I have hereto affixed my signature in the presence of two witnesses.

WILLARD O. WHITE.
